G. H. BENJAMIN.

EVAPORATOR.

APPLICATION FILED JUNE 27, 1917.

1,280,641.

Patented Oct. 8, 1918.

UNITED STATES PATENT OFFICE.

GEORGE HILLARD BENJAMIN, OF NEW YORK, N. Y.

EVAPORATOR.

1,280,641.

Specification of Letters Patent.

Patented Oct. 8, 1918.

Application filed June 27, 1917. Serial No. 177,211.

To all whom it may concern:

Be it known that I, GEORGE HILLARD BENJAMIN, a citizen of the United States, residing at New York, in the county and State of New York, have invented certain new and useful Improvements in Evaporators, of which the following is a specification.

My invention relates to evaporators of the type used on shipboard, and designed to separate water from salt carried by the water.

In practice it has been found that where evaporators are used upon vessels, for instance, torpedo boats, which are subjected to considerable movement by wave influence, that the violent agitation of the water in the evaporator causes the water to mix with the vapor and flow to the condenser, or in other words, causes the evaporator to prime, with the result that instead of obtaining water containing not to exceed one-half grain of salt per gallon, the water frequently contains from two to three grains per gallon, which renders it unfit for drinking or steaming purposes.

In Patent No. 1,225,118 granted to F. T. Evans on May 8, 1917, there is described a method of superheating the vapor after it leaves the evaporator, by which the salt which is carried over by the vapor, under conditions specified, is eliminated, and in the drawing of such patent there is shown an evaporator and a separate superheater.

In my improved construction, as illustrated in the drawing of this application, the evaporator and the superheater are combined within one structure, which arrangement is not only convenient but economical in the results obtained. My construction further involves certain new features, as for instance, the design and construction of the heating coils, the design and construction of the apparatus for carrying the heating coils, so that they may be supported within and readily withdrawn and supported without the receptacle; the construction of the diaphragm introduced between the lower and upper portions of the receptacle wherein the vapor is first divided and then subsequently superheated, and also various other features of construction which will be referred to in the specification and particularly pointed out in the claims.

The accompanying drawings will serve to illustrate my invention, in which Figure 1 is a vertical section looking toward the right, taken on the line I—I of Fig. 3.

Fig. 2 is a perspective view of one of the heating units.

Fig. 3 is a vertical section taken on the line III—III of Fig. 1.

Fig. 4 is a vertical section and partial elevation, showing the receptacle and the doors, heating units and supports for the heating units removed from the receptacle.

Fig. 5 is a section on the line V—V of Fig. 1 looking downward.

Referring to the drawings. 6 indicates the receptacle. The receptacle is divided into two chambers 7, which is the largest, 70 and 8 which is the smallest and is superposed on 7. Situated between these chambers is a shield or diaphragm 9, the upper surface of which is inclined toward the center, and connected to a pipe 10 which leads 75 out of the receptacle, best shown in Fig. 3. The chambers 7 and 8 are provided with doors 11 and 12. The door 11 is supported on rollers 13, which are situated outside of the receptacle. 6 Connected to the inner side 80 of the doors 11 and 12, are heating units 14 (see Fig. 2). These heating units consist of a plurality of elements each consisting of two head portions or manifolds 15 arranged horizontally, and tube portions 16 arranged 85 vertically. The head portions are hollow and the tube portions are likewise hollow. The tube portions may be formed integrally with the head portions, or may be formed separately and secured to the head portions 90 in any suitable manner. The tube portions are given a peculiar shape, *i. e.*, that of a tube pinched in opposite directions, so that the horizontal axes of the pinches will be at right angles along the length of the tube 95 (see Fig. 5). In Fig. 2 the first pinch is indicated at 17, the second at 18, and so on. The object of this construction of tubes, is to make a passage for the steam which shall be narrow but broad, the tubes changing 100 their long diameter successively along the tube thereby facilitating the transfer of heat from the steam to the water in the receptacle. The heating elements are placed one behind the other, and connected by 105 means of pipes 19 which are closed at one

end by a screw threaded cap 20, and provided with side openings 21 arranged to communicate with the interior of the horizontal heads 15 of the heating elements. 5 The other ends of pipes 19 are provided with screw threads 22 which engage corresponding screw threads formed in tubular castings 23. Each of the castings 23 is provided with a flange 24 adapted for attachment to the outer side of the door 11. The heating units are also supported by means of rods 25 which pass through spacing sleeves 26 and through eyes 27 in extensions 28 of the heads 15. The construction of the 10 heating unit in the chambers 7 and 8 is the same, and the same figures apply.

The door 11 is secured to the receptacle by means of bolts 29. The door 12 in chamber 8 is secured to the receptacle by the bolts 20 30. On the front of the door 12 is a projection 31 having an eye, which is adapted to coöperate with a link 32 carried by arm 33, pivotally mounted at 34 on the top of the chamber 8. When the door 11 is removed from the chamber 7, it is carried by the rollers 13; when the door 12 is removed from the chamber 8 it is carried by the arm 33 and link 32. When the doors are removed with the heating units 14 attached, 25 the interior of the receptacle can be easily cleaned, and scale or salt deposit removed from the heating units.

Connected to the top of the chamber 8 and to the pipe 19 connected to heads 15 of the heating unit in such chamber, is a pipe 35, through which steam may be introduced to the heating unit in the chamber 8. 36 is a similar pipe through which the steam may be passed when leaving the heating unit in 40 the chamber 8. 37 is a union connecting pipe 36 to a pipe 38 connected with the heating unit in chamber 7, and 39 is a pipe through which steam leaving the heating unit in chamber 7 may be passed.

45 The operation of my device will be readily understood. Steam at high temperature is introduced into the receptacle through the pipe 35, passes through the heating unit in chamber 8, thence by pipe 36 to pipe 38, to heating unit in chamber 7, thence by pipe 39 out of the receptacle. The steam entering the chamber 8 is at high temperature; the steam entering the chamber 7 is at a lower temperature. The effect of the passage 50 of the steam is to cause volatilization of the water in chamber 7. The vapor rising therefrom passes through passage 40 into the chamber 8 wherein the vapor is subjected to a much higher degree of temperature by 55 the steam passing through the heating unit in chamber 8. Any water or salt which is deposited from such vapor, falls on the top of the diaphragm 9, from which it may be taken out of the receptacle through the 60 pipe 10.

As it is impossible to superheat vapor in the presence of water, the diaphragm 9 is interposed between the water in the chamber 7 and the vapor in chamber 8, which diaphragm, acting in conjunction with the vapor passing through the passage 40, serves to create an effective separation of the water in chamber 7 and the vapor in chamber 8. 70

It will be observed that the salt water 41 in chamber 7, is shown as carried to the top of the head of the heating unit, in this chamber, thereby practically covering the heating unit, and thus taking advantage of all of the heat units passing through the chamber. The diaphragm plus the vapor pressure in chamber 8, serves to prevent the water in chamber 7 from being thrown into the chamber 8 in case of agitation of the vessel on which the evaporator is used. The final vapor passes out of the chamber 8 by pipe 42. To wash out the evaporator, water may be introduced through the pipe 43 or pipe 44, and withdrawn through the pipe 45.

Among the advantages of the construction described is, that the heavy deposit of salt may be allowed to accumulate on the sides and bottom of the chamber 7 and also on the top of the diaphragm 9, which acts as a non-conductor of heat without in any wise interfering with the movement in and out of the doors which support the heating unit. The construction of the heating units is such that the maximum value of the heat transmitted is obtained, and the exterior surface of such unit easily scaled without liability of injuring the tubes. 90

95 The construction as a whole is such, that the whole of the tubes may be immersed in the salt water, thus preventing the setting free of chlorin gas, and without danger of 100 priming.

Having thus described my invention, I claim:

1. An improvement in an evaporating apparatus, comprising a containing shell, a diaphragm dividing said shell into two chambers, a heating unit for each chamber, each heating unit consisting of a plurality of horizontally disposed head portions and interposed vertically disposed tubes, said tubes pinched at intervals along sections of their length, said pinchings having their long axes at right angles to adjacent pinchings, and means for connecting the heating units together in series located exterior to the containing shell. 110

115 2. An improvement in an evaporating apparatus, comprising a containing shell, a diaphragm of less diameter than the largest diameter of the shell, interposed to divide said shell into two chambers, a heating unit in each chamber, and means for connecting the heating units together in series exterior to the containing shell. 120

3. An improvement in an evaporating ap- 130

paratus, comprising a containing shell, a diaphragm dividing said shell into two chambers, removable doors for each of said chambers, a heating unit in each of said chambers mounted upon the removable doors, means for connecting the heating units together in series exterior to the containing shell, and separate means for supporting the doors and heating units when removed from the shell.

4. An improvement in an evaporating apparatus, comprising a containing shell, a diaphragm dividing said shell into two chambers, a removable door for each chamber, a heating unit in each chamber connected to and supported by the inner side of the doors, a swinging support for the door and heating unit of the upper chamber located exterior to the shell, and a wheeled support for the

door and heating unit of the lower chamber located exterior to the shell.

5. A heating unit comprising a plurality of elements, each element consisting of horizontally disposed head portions or manifolds and a series of interposed vertically disposed tubes, each tube pinched at intervals along sections of its length, said pinchings having their long axes at right angles to adjacent pinchings, together with means for connecting the plurality of elements together.

In testimony whereof, I affix my signature, in the presence of two witnesses.

GEORGE HILLARD BENJAMIN.
